UNITED STATES PATENT OFFICE.

HOWARD J. STACH, OF HARTFORD, CONNECTICUT, ASSIGNOR TO NATIONAL MACHINE COMPANY, OF HARTFORD, CONNECTICUT, A CORPORATION OF CONNECTICUT.

GUARD FOR PLATEN-PRESSES OR THE LIKE.

1,258,372.

Specification of Letters Patent.

Patented Mar. 5, 1918.

Application filed April 17, 1916. Serial No. 91,628.

To all whom it may concern:

Be it known that I, HOWARD J. STACH, a citizen of the United States, residing at Hartford, Hartford county, and State of Connecticut, have invented and discovered certain new and useful Improvements in Guards for Platen-Presses or the like, of which the following is a specification.

The present invention relates to guards for printing and other machinery and consists in the combinations and arrangements of parts hereinafter described and particularly set forth in the accompanying claims.

The purpose of the invention is to provide an automatically operated guard for the platens of printing and other presses for protecting the hands of the operator when placing the sheets, which guard will afford the maximum efficiency with minimum mechanism, and wherein the same will not be subjected to any appreciable wear or require care in its use.

The invention has for its further purpose to provide a platen guard which is built in, or as, a part of the press, as distinct from an adjunct to the machine, and which is not in itself dangerous in the event that the operator's hands should become engaged between the guard and the platen.

The invention is shown by way of illustration in the accompanying drawings, wherein:

Figure 1 is a side elevational view of a press equipped with the platen guard,

Fig. 2 a rear view of the platen showing the guard thereon,

Fig. 3 a detail side elevation of the platen and guard in normal or retracted position, and

Fig. 4 a similar view showing the parts in operative position.

Referring to the construction in detail, 1 represents the bed of the printing press or other machine, and 2 the platen thereof that operates after the ordinary manner, and which carries the guard adapted to be automatically operated through the movement of the platen to forcibly remove the hands of the operator from a position that would otherwise result in injury thereto.

The guard consists of a bar 3 disposed transversely of the platen 2, and said bar is mounted on the platen by a pair of bars 4 that fit and work within the two grooves

5. Said grooves are of sufficient depth to

allow the bars 4 to fit wholly therein to the end that the guard will form a part of the press, as distinct from an adjunct thereto with its attendant objections and general detraction from the appearance of the machine. The upper edge of the platen 2 is also cut away or grooved, as at 6, to receive the guard bar 3, after the manner shown in Fig. 3.

The guard carrying bars 4 are held in position and allowed to operate in the slots 5 by the clips 7 secured to the back of the platen and overlying said slots, as clearly shown in Fig. 2. At their lower ends said bars 4 carry projecting members or feet 8 that have for their purpose to engage with the pair of pins 9 on the shelves of the frame 10 and cause the guard bar 3 to be raised on the inward or closing movement of the platen; and on the outward movement thereof, said guard is automatically lowered by gravity, and this movement is assisted by the pair of springs 11 whose respective ends are anchored to the platen and connected to the bars 4, as shown.

The guard, as a whole, is so constructed that injury will not result to the operator in the event of his hand being caught between the guard and the platen, and this provision is further insured since the guard recedes gently with the aid of the two light springs. It will therefore be seen that the guard is not, in itself, a dangerous attachment to the press.

It is obvious that those skilled in the art may vary the details of construction and arrangement of parts without departing from the spirit of my invention, and therefore I do not wish to be limited to such features except as may be required by the claims.

Having thus fully described my said invention, what I claim as new and desire to secure by Letters Patent, is:

1. The combination with a printing press or like machine having a platen, of a platen guard therefor comprising a bar disposed along the upper rear edge thereof, a pair of bars lying within and flush with the surface of the platen and carrying said guard bar, members on the lower ends of said pair of bars projecting rearwardly therefrom, fixed members on the frame of the press adapted to engage with said projecting members on the bars and automatically

raise the guard, and retraction springs engaging said pair of bars operable to withdraw said guard, substantially as set forth.

2. The combination with a printing press or like machine having a platen provided with a groove along the upper rear edge thereof and having a pair of vertically disposed grooves in the back thereof, of a platen guard comprising a bar adapted to fit within the first mentioned groove, a pair of bars lying within the pair of grooves and carrying said guard bar, members on the lower ends of said pair of bars projecting rearwardly therefrom, a pair of pins fixedly

mounted on the frame of the press adapted to engage with said projecting members on the bars and automatically raise the guard, and retraction springs engaging said pair of bars operable to withdraw said guard bar, substantially as set forth.

In witness whereof, I have hereunto set my hand and seal at Hartford, Connecticut this 31st day of March, A. D. nineteen hundred and sixteen.

HOWARD J. STACH. [L. S.]
